TOY GEAR

Earl Weston Farmer, Deephaven, Minn.

Application December 20, 1946, Serial No. 717,386

5 Claims. (Cl. 74—449)

1

My invention relates to toy gears and has for an object to provide a sectional gear, the parts of which may be used for a number of different purposes.

An object of the invention resides in providing a mounting in the form of a wheel having a plate-like web and to which the elements of the gear may be attached.

Another object of the invention resides in constructing the gear with elements, each having two substantially angular edges and a circumferential edge connected therewith and in providing teeth at the circumferential edges of said elements.

A still further object of the invention resides in constructing one of the angular edges longer than the other.

A feature of the invention resides in providing rows of holes spaced equal distances from the angular edges of said elements for the reception of bolts or other fastening means for attaching the elements to the mounting.

An object of the invention resides in providing a hole at the corner formed between the angular edges of each gear element and common to both rows of holes.

Another object of the invention resides in arranging the elements upon the mounting in a manner such as to leave an opening therebetween at the center of the gear and through which a bushing carried by the mounting or the supporting shaft may extend.

A still further object of the invention resides in providing a notch in each element for attaching a chain thereto.

Other objects of the invention reside in the novel combination and arrangement of parts and in the details of construction hereinafter illustrated and/or described.

In the drawings:

Fig. 1 is a plan view of a gear illustrating an embodiment of my invention.

Fig. 2 is a perspective view of the mounting used with the invention.

Fig. 3 is a perspective view of one of the gear elements used with the invention.

Fig. 4 is a perspective view of a toy turning bar illustrating another use of one of the gear elements of the invention.

Fig. 5 is a perspective view of a span of a toy draw-bridge illustrating still another use of a gear element of the invention.

Fig. 6 is a view similar to Fig. 1 of a modification of the invention.

My invention comprises primarily a number of

2

gear elements indicated at 10, 11, 12 and 13 in Fig. 1, which are attached to a mounting 15. These parts will now be described in detail.

The mounting 15 is constructed from sheet metal being formed with a planiform disc-like web 16 from which a flange 17 issues. The flange 17 is disposed at the outer periphery of the web 16. At the center of the web 16 is mounted a hub 18 which is formed with a bore 19 extending through said hub and web. This bore is adapted to receive a shaft on which the gear is to be mounted and is adapted to be held attached to said shaft by means of a set screw 21 screwed into the hub 18. The mounting 15, in addition to serving as a support for the gear elements, is shaped so as to form a wheel which may be used for various purposes in the construction of mechanical toys.

The web 16 of mounting 15 is formed with a number of radial slots 22. These slots are of appreciable length and extend to within a short distance of the hub 18 and the flange 17. In addition to these slots, other and shorter slots 23 are employed which are disposed intermediate the slots 22 and which extend from adjacent the flange 17 toward the hub 18. These slots, however, fall short of the said hub. In a radial alignment with the slots 23 are formed holes 24 which are disposed near the hub 18. In addition, other holes 25 are employed which are spaced near the flange 17 and are arranged the same distance from the slots 22 as the holes 24.

Inasmuch as all of the gear elements 10, 11, 12 and 13 are identical in construction, only the gear element 10 has been shown in detail and will be described. This gear element is shown in Fig. 3 and is constructed from sheet metal and is formed with two substantially angularly extending edges 26 and 27 and a circumferential extending edge 28 connecting the two edges 26 and 27. Along the edge 28 are formed a number of gear teeth 29. The edge 27 is somewhat longer than the edge 26 so that the center of the circumferential edge 28 falls outwardly beyond the edge 27 and inwardly of the edge 26. Along the edges 26 and 27 of the gear element 10 are formed two rows of holes 31 and 32. These holes are the same distance from the edges 26 and 27 and include a hole 33 which is common to both rows and which is disposed at the corner 34 formed between the edges 26 and 27. The holes 31 and 32 are spaced the same distance apart. The gear elements 10, 11, 12 and 13 are adapted to be arranged upon the mounting 15 as shown in Fig. 1. When so disposed, the holes 32 and 33 register with the

holes 24 and the slots 23. Also, the holes 31 register with the slots 22 and holes 25. By the use of bolts 35 extending through these various holes and slots, the elements may be bolted to the web 16 of the mounting 15. It will be observed that the various holes and slots are so arranged that the circumferential edges 28 of the various gear elements form a circle concentric with the axis of the bore 19 of hub 18 and so that an opening 36 is formed between the various edges 27 of the 10 said elements and through which the hub 18 extends. The teeth 29 of the elements are so arranged that the same are continuous throughout the gear when the elements are disposed as shown in Fig. 1. When the parts are so assembled, a 15 complete gear is formed which may be used for numerous purposes in the building of construction toys.

The gear elements of my invention are preferably constructed with their angular edges at right angles to one another as shown in the drawings. When so formed, the said elements may also serve as gusset plates for attaching various structural members together. In Fig. 4, a toy turning bar has been shown which comprises a base 41 channel-shaped in form and having a web 42 and flanges 43 and 44 depending therefrom. These flanges are formed with holes 45 spaced the same distance apart as the holes 31, 32 and 33 of the gear elements of the invention. The said turning bar includes two uprights 46 which overlie the flanges 43 and 44. These uprights have holes 47 formed in the same, the uppermost of which receives a bar 48. In supporting the uprights 46, two gear elements 49 are employed which are identical with the gear element 10. These gear elements are disposed between the flanges 43 and 44 of the base 41 and the uprights 46. Bolts 51 extend through the holes 31 in the elements 49 and the registering holes 47 in the said uprights. Other bolts 52 extend through the holes 32 in the gear elements 49 and through the corresponding holes 45 of the flanges 43 and 44. Other bolts 53 extend jointly through the uprights 46, the holes 33 in the gear elements 49 and also through certain of the holes 45 in the flanges 43 and 44 of the base 41. In this manner, the gear elements are used to brace the uprights 46 so that the same will be held in proper position.

One of the gear elements of my invention may also be used as a section of a gear. In Fig. 5, I have shown a span 55 of a draw-bridge which includes two spaced frames 95 and 195. Frame 95 comprises a horizontal frame member 56, a vertical frame member 57 and a diagonal frame member 58. Frame 195 comprises a horizontal frame member 156, a vertical frame member 157 and a diagonal frame member 158. These frames are connected together by bolts 59 and 159 which extend through said frame members and through spacers 96 and 97 disposed at the outer corners of the two frames. The said frame members at their bases straddle a base 65 having a web 98 and flanges 99 depending therefrom. These flanges are formed with spaced holes 100 similar to the holes 45 in base 41. A shaft 61 extends through the members 56, 57, 156, 157 and through the end holes 100 in the flanges 98 and 99 of base 65. This shaft forms a pivot for supporting the span 55 for swinging movement.

One of the gear elements of the invention, which is indicated at 62 in Fig. 5, is attached to the members 56 and 51 of frame 95 by means of bolts 63. These bolts extend through the holes 31 and 32 of the gear elements and also through

certain of the holes 64 in the members 56 and 51. Suitable spacers 70 are placed between the gear element 62 and members 56 and 51. The base 65 has attached to it, by means of bolts 66, two uprights 67 and 167 which rotatably support a shaft 68. Said shaft has formed on it, a crank 69. Mounted on the shaft 68 is a sprocket wheel 71. A chain 72 is attached to both the gear element 62 and to the sprocket 71. This is accomplished by forming the said gear element and sprocket with notches 72 and 73 into which the last links of the chain are hooked. When the crank 69 is turned, the chain 72 causes the gear element 62 to rotate about the shaft 61 and to raise the span 55 of the draw-bridge. It will be noted that the gear element 62 is mounted so that the long edge 27 of the same is disposed vertically. This gives the greatest leverage on the said element through the chain 72 when the crank 69 is first operated. In this manner, the draw-bridge is easily raised and in addition, travels slowly at the beginning of its movement.

In Fig. 6, I have shown a modification of the invention. In this device, a mounting 81 is employed which is similar to the mounting 15. This mounting has attached to it, four gear elements 82, 83, 84 and 85. All of these gear elements are identical in construction and only the gear element 82 will be described in detail. This element has a circumferential edge 86 and two radial edges 87 and 88. The edges 87 and 88, if extended, intersect the axis of the hub 89 of the mounting 81. The apex of the element formed between the edges 87 and 88 is cut away as indicated at 91 so that when the various elements are assembled, an opening 92 is formed therebetween and through which the hub 89 extends. The various gear elements are attached to the mounting 81 by means of bolts 93 which extend through said elements and through the mounting 81.

The advantages of the invention are manifest. The gear elements may be assembled to form a fairly large gear. These elements may also be used separately for various other uses such as gusset plates, quadrants and gear segments. The parts are extremely inexpensive to fabricate and are easily and quickly used for the intended purposes.

Changes in the specific form of my invention, as herein described, may be made within the scope of what is claimed without departing from the spirit of my invention.

Having described my invention, what I claim as new and desire to protect by Letters Patent is:

55. 1. A gear comprising a mounting, a plurality of gear elements attached to said mounting, said elements each having two angularly disposed edges, one longer than the other, and a circumferential edge connecting the angular edges 60 and teeth formed on said circumferential edges, said elements being arranged on said mounting with the short edge of one element disposed adjacent the long edge of the adjacent element to leave an opening at the center of the assembly 65 of elements and with the circumferential edges arranged in the form of a circle, said mounting having a hole therein at the center of said circle and at the locality of said opening.

2. A gear comprising a mounting, a plurality of gear elements attached to said mounting, said elements each having two angularly disposed edges, one longer than the other, and a circumferential edge connecting the radial edges, teeth formed on said circumferential edges, said elements being arranged on said mounting with the

short edge of one element disposed adjacent the long edge of the adjacent element to leave an opening at the center of the assembly of elements and with the circumferential edges arranged in the form of a circle, and a hub attached to said mounting at the center of said circle and extending through said opening.

3. A gear element comprising a plate-like structure having two edges disposed at right angles to one another, and a circumferential edge connecting said first named edges, one of said first named edges being longer than the other, teeth formed on said circumferential edge for engagement with a chain and a notch in one of said first named edges for the reception of the end of the chain to secure the same to said element.

4. A gear element comprising a plate-like structure having two edges disposed at right angles to one another, and a circumferential edge connecting said radial edges, teeth formed on said circumferential edge and a row of holes formed along each of said first named edges and the same distance therefrom, said holes being spaced from one another the same distance, there being one hole common to both rows and located at the corner between said first named edges.

5. A gear comprising a mounting, a plurality of gear elements attached to said mounting, said

elements each having two angularly disposed edges, one longer than the other, and a circumferential edge connecting the angular edges with teeth formed on said circumferential edge, said elements being arranged on said mounting with the short edge of one element disposed adjacent the long edge of the adjacent element and with the long edges tangent to a circle concentric with the axis of said gear and with the circumferential edges arranged in the form of a circle.
